(57) **CLAIM**

I claim the ornamental design for a watch casing, as shown and described.

DESCRIPTION

FIG. 1 is a perspective view of the watch casing according to my design;

FIG. 2 is a top plan view of the watch casing according to my design;

FIG. 3 is a bottom plan view of the watch casing according to my design;

FIG. 4 is a right side view of the watch casing according to my design;

FIG. 5 is a left side view of the watch casing according to my design;

FIG. 6 is a front elevation view of the watch casing according to my design; and,

FIG. 7 is a back elevation view of the watch casing according to my design.

The broken line showing in FIGS. 1-4, 6 and 7 of the watch casing is for illustrative purposes only and forms no part of the claimed design.

1 Claim, 4 Drawing Sheets

FIG. 1

FIG. 2

FIG. 3

FIG. 4

FIG. 5

FIG. 7

FIG. 6
